ABSTRACT OF THE DISCLOSURE

A slightly tapered support element for insertion within the opening defined by a heating element spider. The support member having generally cylindrical outward configuration and having plural vertical ridges extending outwardly therefrom with the lower portion of the ridges being cut out by a circular die to form a notch in each vertical ridge at the lowermost portion of the cylindrical member. The notch being snapped onto horizontal ridges extending inwardly from each web element of the spider.

BACKGROUND OF THE INVENTION

The heating elements employed in electric ranges generally include a spider formed by metallic web members for supporting generally circular heating means per se. A central opening is generally provided by the element forming the spider and it is conventional practice to provide a central supporting member having a medallion or other means supported on its upper surface within this open space. The supporting member normally comprises means for merely supporting a design or other indicia indicative of the manufacturer or seller of the heating unit. However, in recent years the development of heat sensitive thermostat means for controlling the current to each burner has resulted in the use of such central support members for supporting heat sensitive means to prevent overheating of the unit.

In all cases, whether the central support member has been for the purpose of merely supporting identifying indicia or for supporting more sophisticated elements such as thermostat control, there has been a problem of providing adequate means for retaining the support member within the confines of the spider. Such retaining means should be easily and quickly operated so that the support member can be placed within the confines of the spider with a minimum effort and should also provide a completely reliable connection capable of sustaining the support member in position during the normal shocks and vibrations incident with use of the heating element. The support member should also be easily removable from the spider.

Previous methods of attaching such support members have included the use of tabs which are inserted through holes in the spider and subsequently bent into position to provide a clamping connection with the spider. An example of such a structure is found in U.S. Patent No. 2,877,334. Other support-spider connecting structures have included threaded connections, detents and the like. However, such structures have not been reliable in that they are either too easily disconnected from the spider or alternatively, they are too hard to disconnect.

SUMMARY OF THE INVENTION

The central support member in the preferred embodiment comprises a slightly tapered conical, hollow cup shaped member which tapers outwardly from the top to the bottom thereof and which has a plurality of outwardly extending ridges oriented vertically in its outer surfaces. The lower portion of the outwardly extending ridges is cut out by a semi-circular die member to provide a notch

2

in the outwardly extending ridges with the lower portion of the notch being formed by an outwardly extending bottom flange element. The aforementioned notch is dimensioned so as to snugly snap over and engage a horizontal inwardly extending ridge on each of the flat web members forming a heating element supporting spider. The web members are connected to define an opening into which the support member is inserted so that each notch snaps over its respective horizontal ridge. This construction enables the easy insertion of the support member within the confines of the spider and also enables the removable support from within the confines of the spider without undue effort. The invention, therefore, provides a solution to the need for easily insertable and easily removable circular support members for heating elements. The support member is not susceptible to separation from the spider due to the normal shocks and vibrations incident with the use of the heating element.

It is a primary object of this invention to provide new and improved central support members for use in electrical heating units.

Yet another object of this invention is the provision of a new and improved medallion support member for use in electrical heating units.

Yet another object of this invention is a new and improved central support member for supporting a thermostat in a heating unit.

BRIEF DESCRIPTION OF THE DRAWINGS

FIGURE 1 is a top plan view of a preferred embodiment;

FIGURE 2 is a sectional view taken along lines 2—2 of FIGURE 1;

FIGURE 3 is a side elevation of the support member; and

FIGURE 4 is a sectional view taken along lines 4—4 of FIGURE 3.

DESCRIPTION OF THE PREFERRED EMBODIMENT

The preferred embodiment of the invention is for a metallic central support member 8 having a medallion plate 9 in the shape of indicia, a trademark or other design on its top surface. The support member is inserted within a central opening defined by a spider 10. The spider comprises three metallic web members 12 connected by a rivet or weld at their outer ends to define a generally triangular central opening 16. Each web 12 has an inwardly extending horizontal ridge 18 (FIGS. 1 and 2) extending into the opening 16. A heating coil 20 (shown in dashed lines) rests upon the upper surface of spider 10 as shown in FIGURE 1.

The support member 8 is formed of a hollow shell or cup member generally having an outer wall 24 which is slightly tapered upwardly from a bottom flange 26 as shown in FIGURE 3. Consequently, the outer wall 24 defines a slightly tapered conical section. A plurality of vertical ridges 28 extend outwardly from outer wall 24 as shown in FIGURE 1. The ridges 28 are equidistantly spaced about the periphery of outer wall 24 and the bottom portion of each ridge is terminated by a semi-circular die having its center slightly below the bottom of flange 26 which is moved radially inwardly to provide a cut defined by edge 32. Consequently, a notch 34 (FIG. 4) is formed in each vertical ridge and has a bottom termination in flange 26. Each notch 34 snugly engages its respective horizontal ridge 18 as shown in FIGURE 2.

The top of the support member 8 in the preferred embodiment has a design in the form of a plate attached thereto. However, it should be understood that the design could be merely printed or painted on the top of

the support member 8. It should also be clearly understood that the support member can serve to support any desired structure such as a thermostat for controlling the heat coils if desired.

The support member 8 is inserted within opening 16 upwardly from the bottom of the opening so that the vertical ridges 28 engage their respective horizontal ridges 18. The entire structure is then shaped into position by additional upward pressure so that each notch 34 embraces its respective horizontal ridge 18. The member is then fixedly supported within the confines of the spider and will remain therein. The member 8 is constructed of somewhat flexible metal stock and the structure can be removed by forcefully pressing downwardly upon the top of the member 8. Such downward pressure causes the portion of the member adjacent notch 34 to move inwardly to allow the shell to be removed from opening 16.

While the preferred embodiment is drawn to a shell having three ridges to be used with a spider formed by three webs, it should be understood that any number of ridges could be employed for use with a like number of horizontal ridges on associated metallic web members. It should also be understood that it is not absolutely necessary that the shell member be generally circular as viewed from above in that the shell could have linear portions extending between respective vertical ridges if desired.

While only one embodiment of the present invention has been particularly shown and described, it should be apparent that various other modifications may be made within the spirit and scope of the invention.

I claim:

1. In a range top heating unit of the type having a heating element supporting spider formed of plural metallic webs connected to define a central opening with each web having a horizontal ridge extending into said opening, a new and improved support member received within said opening, said support member comprising:

a hollow shell member having an outer surface dimensioned to loosely fit within said opening; and

a plurality of generally vertical outwardly extending ridges formed in said hollow shell and having a lower termination above the bottom of said shell

formed by a cutout portion defining a notch in said ridge and the bottom of said shell, each of said notches being vertically dimensioned so that it snugly engages one of said horizontal ridges to enable said shell to be retained in said central opening.

5 2. The device of claim 1 wherein said hollow shell includes an outwardly flared bottom flange.

3. The device of claim 2 wherein said cutout is defined by a generally semi-circular edge in said shell as viewed from a radial position aligned with one of said vertical ridges.

10 4. The device of claim 3 wherein the diameter of said cutout is substantially greater than the width of said vertical ridge.

15 5. The device of claim 4 wherein the center of curvature of said semi-circular cutout is beneath said bottom flange.

6. The device of claim 2 wherein said hollow shell comprises a slightly tapered conic section of upwardly tapering configuration.

20 7. The device of claim 3 wherein said hollow shell comprises a slightly tapered conic section of upwardly tapering configuration.

8. The device of claim 4 wherein said hollow shell comprises a slightly tapered conic section of upwardly tapering configuration.

25 9. The device of claim 5 wherein said hollow shell comprises a slightly tapered conic section of upwardly tapering configuration.
